DESIGN FOR A THREAD CONTROL DEVICE FOR KNITTING MACHINES AND THE LIKE

Rudolph Hug, West Reading, Pa., assignor to
Textile Machine Works, Wyomissing, Pa., a
corporation of Pennsylvania

Application June 19, 1937, Serial No. 69,919

Term of patent 14 years

To all whom it may concern:

Be it known that I, Rudolph Hug, a citizen of the United States of America, residing at West Reading, in the county of Berks and State of Pennsylvania, have invented a new, original, and ornamental Design for a Thread Control Device for Knitting Machines and the like, of which the following is a specification, reference being had to the accompanying drawing, forming part thereof.

Figure 1 is a top plan view of a thread control device for knitting machines and the like, embodying my new design;

Fig. 2 is a side elevational view of the device shown in Fig. 1;

Fig. 3 is a rear elevational view of Fig. 2; and

Fig. 4 is a front elevational view of Fig. 2.

I claim:

The ornamental design for a thread control device for knitting machines and the like, as shown.

RUDOLPH HUG.
